(57) **CLAIM**

The ornamental design for a brooch, as shown and described.

DESCRIPTION

FIG. 1 is a front, perspective view of a brooch according to my new design;

FIG. 2 is a rear, perspective view thereof;

FIG. 3 is a side, perspective view thereof;

FIG. 4 is an opposite side, perspective view thereof;

FIG. 5 is a top plan view thereof; and,

FIG. 6 is a bottom plan view thereof.

The dashed lines are for environmental purposes only and form no part of this invention.
